UNITED STATES PATENT OFFICE.

WILLIAM A. REAPER, OF MONROE, MICHIGAN.

DESIGN FOR A COMPARTMENT-JAR.

55,319.

Specification for Design.

Patented May 25, 1920.

Application filed March 6, 1920. Serial No. 363,834. Term of patent 14 years.

To all whom it may concern:

Be it known that I, WILLIAM A. REAPER, a citizen of the United States, residing at Monroe, in the county of Monroe and State of Michigan, have invented a new, original, and ornamental Design for a Compartment-Jar, of which the following is a specification, reference being had to the accompanying drawing, forming part thereof.

Figure 1 is an elevation of a compartment jar showing my new design.

Fig. 2 is a plan view thereof.

I claim:

The ornamental design for a compartment jar, as shown.

WILLIAM A. REAPER.

Witnesses:

FRED J. SILL,
WM. G. GUTMANN.
